UNITED STATES PATENT OFFICE.

GEORGE A. FISHER AND JOHN ALFRED MORRISON, OF MINNEAPOLIS, MINNESOTA.

DEVICE FOR REMOVING OBSTRUCTIONS FROM CLOSET-BOWLS, &c.

1,051,992.

Specification of Letters Patent.

Patented Feb. 4, 1913.

Application filed February 19, 1912. Serial No. 678,593.

To all whom it may concern:

Be it known that we, GEORGE A. FISHER and JOHN A. MORRISON, citizens of the United States, residing at Minneapolis, in the county of Hennepin and State of Minnesota, have invented certain new and useful Improvements in Devices for Removing Obstructions from Closet-Bowls, &c., of which the following is a specification.

10 Our invention relates to a device for removing obstructions from closet bowls, sink traps, and other inclosed portions of plumbing where matter may accumulate and cause clogging and stoppage. Where such stoppage occurs it is usually customary to attempt to force the matter through by means of a suction cap on the end of a stick commonly termed a "plumber's friend", and if this fails to dislodge the clogging material a plumber is required to take the closet or other piece of plumbing apart and remove the obstruction. This frequently results in the creating of leaks, is unsanitary and expensive. Moreover, it necessitates the employment of a skilled workman who frequently is not available when wanted.

15 It is the object of our invention to provide a device which will be capable of being inserted through the irregular and contorted channel to the seat of the trouble, and can then be applied to hook into or grip the clogging matter so as to remove the same from the passage.

The full objects and advantages of our invention will appear in connection with the detailed description thereof and are particularly pointed out in the claims.

20 In the drawings, illustrating the application of our invention in one form,—Figure 1 is a view of our device partly broken away, showing the hooking means extended. Fig. 2 is a view of a fragment of the hook end of the device with the coil broken away showing the hooks in retracted condition. Figs. 3 and 4 are views of different forms of hooks which may be employed.

25 The body of our device comprises a coil of wire 10. This may be ordinary steel wire nickelized or bronzed, and will be of sufficient size and so coiled as to form at the same time a coil having capacity for exerting considerable thrusting pressure and sufficiently flexible to follow the irregularities and sharp turns of the passages through which the coil will be inserted. The ends of the coil may be provided with washers 11

and 12, although this is not necessary as the last coil may be ground off flush and soldered upon the preceding coil which will have the effect of finishing the ends of the washers 11 and 12. The coil as formed provides a flexible tubular member having a considerable degree of stiffness and tensile strength. Within the coil is positioned a wire 13 of spring steel or other stiff and unyielding metal. If desired, instead of the single wire a plurality of wires twisted together may be employed. The wire will be provided with a ring 14 at one end and at the other end with a rigidly connected snap 15. Removably held in this snap is a grappling member 16. As shown in Fig. 1, the grappling member is provided with a plurality of prongs 17 each having an outwardly turned hook 18. In Fig. 4 substantially the same structure is shown excepting that some of the prongs 17 are provided with inwardly turned hooks 19. The grappling member shown in Fig. 3 comprises a pair of tongs 20 each provided with a sharp inwardly turned hook 21 and normally pressed apart by means of a spring 22 between the ends of the tongs away from the hooks 21 and beyond the pivot 23 by which the tongs are secured together. A ring member 24 is loosely secured to the inner ends of the tongs 20 to which the snap member 15 may be connected.

30 In operation, the grappling member, whichever form is used, will be drawn within the tubular coil 10, as shown in Fig. 2, in which position the prongs will be closed and the hook members rendered inoperative. The grapple end of the member 10 will then be inserted into the opening leading from the closet bowl or sink, and owing to its combination of stiffness and flexibility it can be worked around through the tortuous passages until the point of clogging is reached. In some cases it will be possible to push the clogging material down into the drain pipe by direct pressure of the end of member 10. When this cannot be done, which may usually be the case, by pushing on the wire 13 the grapple hook 16 (or 20 if that form is used) will be ejected from the end of member 10 whereupon the spring prongs 17 or the spring actuated tongs 20 will spread. After some little manipulation and twisting the hooks of the grapple member will begin to take hold of the clogging material, whereupon

the operator will through the ring 14 draw upon the wire 13 bringing the grapple back into tubular member 10 and at the same time causing said hooks to firmly grip the 5 clogging material, which may then be withdrawn from the passage.

With this device, anything in the way of paper, rags, hair, soap and similar substances can be removed with absolute certainty, and by the employment of the grapple of Fig. 3 or even that of Fig. 4, such articles as hair brushes, combs, wooden blocks and vegetables may in most cases be successfully grappled and removed.

Our advice is simple in construction, can be made cheaply and provides an efficient means for the purpose. It can be manufactured so cheaply that it may be in any household, where a stoppage can be remedied by the people of the house immediately upon occurrence without resorting to the services of a plumber or other skilled workman.

This device will be found of special value in apartment houses, flat buildings, hotels, office buildings, and similar structures where a large amount of plumbing is involved and the liability of stoppage is considerable.

It will be noted that in coiling the tube the coils of wire will be laid so that each succeeding coil contacts with the one preceding it, and the entire tube will be coiled to lie normally in a straight line. Thus while the tube will be flexible and resilient it will always tend to position itself in a straight line, and by reason of the contracting of the successive coils of the tube will be capable of transmitting thrusting force from end to end whatever the form and degree 40 of curvature it may have been caused to take.

We claim:

1. A device for removing obstructions from passages in plumbing, comprising a tube formed of a coil of wire, a relatively stiff link in the tube, and a grapple on the end of the link composed of a plurality of hooked members, said grapple being movable entirely out of said tube, said members being closed together when the grapple is drawn within the tube and being spring-actuated to spread apart when the grapple is ejected from the tube.

2. A device for removing obstructions from passages in plumbing, comprising a flexible resilient open-ended tube, a relatively stiff wire freely movable within said tube, and a grapple loosely connected with the end of said wire and freely movable entirely out of said tube, said grapple comprising a plurality of spring fingers normally tending to spread apart and each provided with an outwardly turned hook.

3. A device for removing obstructions from passages in plumbing, comprising a flexible resilient open-ended tube, a relatively stiff wire freely movable within said tube, and a grapple loosely connected to the end of said wire and freely movable entirely out of said tube, said grapple comprising a plurality of spring fingers normally tending to spread apart, some of said fingers being provided with outwardly turned hooks and other of said fingers having inwardly turned hooks.

In testimony whereof we affix our signatures in presence of two witnesses,

GEORGE A. FISHER.

JOHN ALFRED MORRISON.
